[57] ABSTRACT

A machine for casting metals under gas pressure of a four-column design is provided. It includes an intermediate plate which is disposed between a bottom plate and a movable plate with a metal duct fastened to it. This closes tightly the reservoir for the melt. Fastened by known means to this plate are the fixed part of the casting mould and the housing sealing it, by means of which and of a connecting element of known design and the attachment of the housing to the movable plate a rigid connection between the plate and the transfer cylinder, disposed on the top plate is achieved by means of the piston rod, connected rigidly to the movable plate.

3 Claims, 3 Drawing Figures

FIG. 1

SERIAL NUMBER 285,661
GROUP ART UNIT 322

FIG. 2

FIG. 3

MACHINE FOR CASTING METALS UNDER GAS PRESSURE

BACKGROUND OF THE INVENTION

This invention relates to a machine for casting metals and alloys under gas pressure, and particularly to a machine in which the displacement of the melt from the reservoir to the casting mould is performed under the action of gas pressure. The closing system of the machine is used for balancing the force, resulting from the pressure in the reservoir for the melt.

Machines for casting under gas pressure are known, in which the reservoir for the melt is tightened independently by means of a separate cover and connecting elements, dimensioned with regard to the working pressure of the process gas. Access to the the furnace (i.e. to the reservoir for the melt) for carrying out service and repair work is provided by removing the superstructures by tilting or lateral displacement by means of special hydraulic cylinders attached to the machine, or by moving it to the side by means of additional handling equipment.

It is the main drawback of this design, that the provision of an access to the furnace (i.e. to the reservoir for the melt) requires the most of additional special mechanisms, and this results in an increase in weight and complexity of control of the machine, and consequently increase in price. Furthermore, a large number of bolt connections must be unscrewed for opening the cover of the furnace, reducing thereby the capacity of the machine and making practically impossible to use it for casting special alloys requiring a metallurgical treatment directly before the casting process itself.

SUMMARY OF THE INVENTION

It is therefore a general object of the present invention to avoid the drawbacks of the aforescribed machines by providing a machine for casting under gas pressure, in which rapid and easy access to the furnace is provided for carrying out service and repair work. The access is provided using the available transfer, closing and other systems.

This object is achieved, according to the invention, by adding to a vertical machine of known four-column design, comprising a bottom plate, a movable plate and a top plate, on which a transfer cylinder for moving the movable plate is attached, in which all plates are connected by four columns. The addition is an intermediate plate, which is disposed between the bottom and the movable plate, which is used simultaneously as a tight cover for the reservoir for the melt, as well as for fastening the fixed part of the casting mould and the housing closing it tightly. The sealing of the reservoir for the melt and the balancing of the gas pressure in it are effected by the force of the transfer cylinder or, in the case of great forces, by a special sealing mechanism of known design (e.g. a wedge or a toggle-lever mechanism), which is provided for sealing the casting mould. In order to provide a rigid connection between the bottom plate, the reservoir for the melt and the intermediate plate, which is needed for balancing the force when separating the mould and stripping the casting from its fixed bottom part, the intermediate plate is pressed against the reservoir for the melt by means of a wedge mechanism. To disengage the furnace for carrying out service and repair work, the intermediate plate and the

movable plate are coupled to the two halves of the casting mould; to the sealing housing, or are directly coupled. The wedge locking of the intermediate plate to the columns is released, and the intermediate plate, casting mould and movable plate are lifted to a required height by means of the transfer cylinder. Thus, the furnace space is exposed, providing an access to the molten metal. The furnace automatically lifted by spring dampers, on the bottom end of which castor wheels are attached, running in special grooves in the bottom plate extending outside the plate by rails and can thus be pulled out of the machine.

BRIEF DESCRIPTION OF THE DRAWINGS

15 The invention may be better understood when explained with reference to the accompanying drawings.

FIG. 1 is a general view of the machine;

FIG. 2 is a section along A—A, according to FIG. 1, showing the mechanism for locking the intermediate 20 plate to the reservoir for the melt;

FIG. 3 is a section along B—B, according to FIG. 1, showing the spring damper for lifting and displacing the reservoir for the melt.

DETAILED DESCRIPTION OF THE PREFERRED EMBODIMENT

The reservoir for the melt 3 is disposed between the bottom plate 1 and the intermediate plate 4, and its sealing in each working cycle is effected by the elastic seal 5, and the force of the gas pressure is balanced by the transfer cylinder 11, attached rigidly to the top plate 10 and connected to the movable plate 9 by means of its piston. This force is transmitted from the intermediate plate 4 to the casting mould 7 or the sealing housing 8 respectively, the movable plate 9, the cylinder 11, the fixed plate 10 and to the columns 2.

In order to provide a continuous rigid connection during operation of the system bottom plate 1, reservoir for the melt 3 and intermediate plate 4, necessary for balancing the force when separating the casting mould 7 and stripping the casting from the fixed part of the mold, the intermediate plate 4 is pressed against the reservoir for the melt 3 by means of a wedge (locking) mechanism, disposed on the upper surface of the intermediate plate on two opposite columns 2. The wedge mechanism consists of wedges 15, guided in parallel guideways 14, driven progressively by a system of regulable in length rods 16 by means of sleeves 17 and a handle 18, supported on one of the columns 2. The lifting of the reservoir for the melt 3 until its bottom separates from the bottom plate 1 at a height "a" and its pulling out of the machine for carrying out service and repair work is effected by means of four spring dampers with castor wheels, attached to the outer wall of the reservoir for the melt. They consist of the castor wheel 19, supported on an axle on the guide 20, and a cylinder 21, attached rigidly to the reservoir for the melt 3. Disposed in the cylinder is the spring 22, regulated in dependence of the mass of the reservoir for the melt by means of a disk 23 and a screw 24.

The operations for pulling out the reservoir for the melt to perform service and repair work and treatment of the alloy are performed, according to the invention, in the following order:

65 By means of the transfer cylinder 11 the movable plate 9 is displaced in its bottom position, in which both halves of the casting mould 7 or the housing 8 sealing

it, respectively, come into contact. The handle 18 of the locking mechanism is turned to the "unlocked" position and the wedges 15 are pulled out of the grooves in the columns 2 by means of the bars 16. Both halves of the casting mould 7 or the housing 8 sealing it are 5 connected, or the movable plate 9 and the intermediate plate 4 are connected directly by means of a connecting element 6 of known design, and by the back stroke of the transfer cylinder 11 the movable plate 9, casting mould 7 and intermediate plate 4 with the metal duct 10 12 fastened to it, are lifted to their top position. The lower end of the metal duct 12 stops at 40-50 mm above the jointing plane of the reservoir for the melt 3, and the reservoir for the melt 3 is lifted by the action of the springs 22 of the spring dampers with castor 15 wheels to the height a and is pulled out of the machine along the grooves in the bottom plate 1 and the rails 13.

The pushing back of the reservoir for the melt 3 into the machine in its initial working position is performed in the reverse order.

What we claim is:

1. An apparatus for casting metal comprising:
  - a. pressurized reservoir means for a melt;
  - b. intermediate plate means positioned above said reservoir means, said intermediate plate means including a metal duct means extending into said reservoir means;
  - c. mould means positioned above said intermediate plate means, wherein said metal in said reservoir means passes into said mould means through said metal duct means;
  - d. column means having slot means therein;
  - e. movable plate means positioned above said mould means in a mould sealing relationship with said intermediate plate means, and locking means comprising guides fixed to said intermediate plate means and wedge means mounted on said column means, said wedge means being forced between said intermediate plate means, said slot means and said guides;
  - f. transfer cylinder means for holding said reservoir means, intermediate plate means, mould means, and movable plate means in the sealing relationship against the pressure in said reservoir means such

that the pressure forces said melt into said mould means; and,

g. column means for supporting said intermediate plate means, said movable plate means, and said transfer cylinder means, said transfer cylinder means comprising a top plate fixed to said column means, a cylinder fixed to said top plate, and piston means extending from said cylinder and coupled to said movable plate means, said intermediate plate means and said movable plate means being movable on said column means.

2. An apparatus for casting metal comprising:

- a. pressurized reservoir means for a melt, said reservoir means including a reservoir and reservoir support means, said reservoir support means comprising a cylinder fixed to said reservoir, spring means within said cylinder, and castor means operably connected to said spring means to raise said reservoir;
- b. intermediate plate means positioned above said reservoir means, said intermediate plate means including a metal duct means extending into said reservoir means;
- c. mould means positioned above said intermediate plate means wherein metal in said reservoir means passes into said mould means through said metal duct means;
- d. movable plate means positioned above said mould means in a mould sealing relationship with said intermediate plate means;
- e. transfer cylinder means for holding said reservoir means, intermediate plate means, mould means, and movable plate means in the sealing relationship against the pressure in said reservoir means such that the pressure forces said melt into said mould means; and,
- f. support means for supporting said intermediate plate means, said movable plate means, and said transfer cylinder means, said intermediate plate means and said movable plate means being movable on said support means.

3. The apparatus of claim 2 wherein said spring means are adjustable.
